UNITED STATES PATENT OFFICE.

HENRI PIEPER, OF LIEGE, BELGIUM.

INTERNAL-COMBUSTION ENGINE.

1,197,951.

Specification of Letters Patent. Patented Sept. 12, 1916.

Application filed June 20, 1913. Serial No. 774,857.

To all whom it may concern:

Be it known that I, HENRI PIEPER, a subject of the King of the Belgians, and residing at Liege, Belgium, have invented certain new and useful Improvements in Internal-Combustion Engines; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

My invention has for its object an explosion or internal combustion engine in which the admission and the exhaust of the gases are controlled by means of a minimum number of auxiliary regulating devices in such a manner as to effect the motion of the auxiliary devices in an extremely simple manner and to render the distributing independent of the direction of rotation of the motor, and to assure also the proper working of the gas control system and of the whole engine. To this end according to my invention the gas distribution of a four stroke cycle internal combustion engine is controlled by employing the main piston itself for opening and closing one or more cylinder orifices serving as passages for the gases and situated toward the end of the stroke, these orifices being connected respectively with the inlet or exhaust pipe by means of one or more suitable auxiliary devices, driven by the engine shaft at half the speed. In this way a four stroke cycle engine is obtained, which has an extremely simple distributing system as regards the form of the controlling devices and their motion. Further this gas distributing system can be employed for both the directions of running of the engine without any modification. Consequently it allows of dispensing with the complicated reversing mechanisms which are indispensable in the usual constructions of four stroke cycle engines. At the same time the method of working of the engine according to my invention differs fundamentally from that of the ordinary engines notwithstanding that all practical requirements are satisfied from both the mechanical and thermal standpoint. Finally in the case of a two cylinder four stroke cycle engine my invention allows of controlling the admission and the exhaust of both

the cylinders by means of the same auxiliary devices working in series alternately with one or the other of the two main pistons used for opening the cylinder orifices 60 toward the end of the stroke, the auxiliary devices serving alternately as a distributor for the orifices of one or other of the two cylinders by connecting these orifices respectively with the inlet and outlet pipe. 65

In the accompanying drawings: Figure 1 represents the embodiment of my invention in a four stroke cycle engine using the atmospheric pressure for introducing the charge. Fig. 2 shows the application of my 70 invention to a four stroke cycle engine, in which the admission is effected under pressure produced by a compressor attached to the main piston. Fig. 3 is a longitudinal section of a two cylinder four stroke cycle 75 engine embodying my invention. Fig. 4 is a horizontal section taken at the level of the cylinder ports of Fig. 3. Fig. 5 is a vertical section taken through the distributing chamber of Fig. 3. Fig. 6 is a crank diagram of the cycle of the two cylinder engine shown in Figs. 3 to 5.

Referring to Fig. 1 the cylinder 1 of the four stroke cycle engine, in which the piston 2 connected with the motor shaft 5 by connecting rod 3 and crank 4 reciprocates is provided at its lower end with one or more orifices 6 which may be put in communication respectively with the exhaust 8 or the inlet 9 by means of an auxiliary slide piston 11 driven by the engine shaft at half speed. The main piston may be provided with a nose 12 serving for directing upward the fresh gases on entering in order to produce a better distributing of the charge 95 throughout the cylinder space.

The engine shown in Fig. 1 works in the following manner: The auxiliary piston 11 approaches its lower deadpoint and opens the communication between the orifice 6 and the exhaust 8, when the working piston 2 opens the orifice 6 after the explosion stroke, and the exhaust of the burned gases takes place. The exhaust is finished by the piston, ascending and reclosing the orifice 6. 105 The residue of burned gases remaining in the cylinder is compressed during the remainder of the upward stroke and expands during the following downward stroke. On the other hand this residue of gases is cooled 110 down during these strokes by the cylinder walls from their original temperature of

about 700° to the temperature of the cylinder walls of about 80°. This reduction of the temperature causes a corresponding diminution of the volume of the gas residue. Consequently at the moment where the piston 2 reopens, toward the end of the downward stroke, the orifice 6, the pressure in the cylinder 1 is considerably below the atmospheric pressure and the fresh charge of air and fuel is drawn in through the orifice 6, which is put in communication at this instant with the inlet 9 by the auxiliary piston approaching now its upper deadpoint. If desired, this suction may be improved by arranging, as shown in Fig. 1, in the exhaust 8 a ventilator 13 which sucks out a greater quantity of burned gases during the exhaust period. Evidently any other suitable means may be employed for increasing the exhaust and the vacuum. The introduction of the fresh mixture will be finished, when the equilibrium is obtained between the pressures existing respectively in the cylinder and in the inlet pipe approximately at the moment that the main piston 2 on ascending recloses the orifice 6. During the remainder of this upward stroke the mixture is compressed and then ignited, whereafter the cycle recommences.

On examining the method of working of the four stroke cycle engine shown in Fig. 1, it will be seen that the exhaust and the admission are controlled in a manner differing from the usual four stroke cycle engines. Both the exhaust as well as the inlet take place toward the end of the piston stroke through orifices which are opened and closed by the working piston itself and a single auxiliary device serves only for directing the gases toward the inlet and the exhaust pipe. Consequently a normal rotary crank and reciprocating rod or similar driving mechanisms can be employed for driving the auxiliary device by the engine shaft at half speed, while in the usual four stroke cycle engines, using a single gas controlling device the driving mechanisms are very complicated in order to obtain the necessary relation of the movement of the auxiliary device to that of the main piston. Further in the engine represented in Fig. 1 the relation of the motion of the distributor piston 11 to that of the main piston 2 may be chosen so that both the pistons arrive at their lower deadpoints at the same moment, thus permitting the use of the distribution system for both directions of rotation of the engine without being obliged to provide special reversing devices as in the usual four stroke cycle engines. This advantage is very useful especially for driving vehicles by means of a four stroke cycle explosion engine acting directly upon the wheels so that the engine is able to run in both directions according to the actual sense

of running of the vehicle. The control of the vehicle is thereby considerably simplified and at the same time the security of the service is increased by using a four stroke cycle engine permitting this condition being satisfied without the usual complicated reversing devices. Further the auxiliary piston works under very favorable mechanical conditions in that only its head surface is exposed to the hot burned gases, its sliding wall being always cooled down. All these advantages are obtained by means of a construction of great simplicity comprising besides the working parts of the engine itself, only a single auxiliary device driven simply by a rotary crank shaft and a reciprocating rod.

It is not absolutely necessary to introduce the fuel, as shown in Fig. 1, through the same cylinder orifice as the combustion air toward the end of the stroke. The fuel may be admitted separately through an orifice independent of the piston, while only the combustion air is introduced through the orifice situated at the end of the cylinder. In this case the fuel is introduced alone or mixed only with the small quantity of air necessary for its vaporization. The valve serving for controlling the fuel admission may be provided, for instance, at the top of the cylinder and be opened automatically by means of the vacuum existing in the cylinder at the end of the suction stroke. The separate introduction of fuel and air will be of a special advantage in the case of heavy fuels. Further instead of the orifice shown in Fig. 1, as common for both the admission and the exhaust, one or more orifices for the inlet and one or more other orifices for the exhaust may be provided in the cylinder toward its lower end, the exhaust orifices being preferably arranged above the admission orifices at a convenient distance. In this case the auxiliary piston works in such a manner as to close the admission orifices during the exhaust period and the exhaust orifices during the admission period. The separation of the cylinder openings for inlet and exhaust gives the advantage of improving the admission and the exhaust of the four stroke cycle engine. In providing only a cylinder orifice serving for both the entering and the escaping gases, the same must be arranged in the cylinder wall at the end of the inward stroke so as to avoid the inconvenience due to the ascending piston partly expelling the charge drawn in. On the other hand a sufficiently long exhaust time requires an orifice opened by the piston at a sufficient distance from its lower dead point. These two requirements of proper working may be easily satisfied by providing besides the orifice serving for the fresh gases, a separate orifice serving only for the escaping gases, which may be sit-

uated at a higher level than the inlet orifice or orifices. In the embodiment of my invention shown in Fig. 2 this separation of the inlet and exhaust cylinder orifices and the independent introduction of the fuel are illustrated. Further the four stroke cycle engine according to Fig. 2 is improved by using the main piston for introducing the combustion air under pressure. The admission orifice 17 is arranged in Fig. 2 at the end of the stroke and the exhaust orifice 18 at a convenient distance thereabove. The auxiliary piston 11 driven by the engine shaft 5 at half the speed serves for closing the orifices 17 during exhaust and the orifices 18 during inlet. The working piston 19 has an elongated portion carrying a compressor piston working in the chamber 23. This chamber 23 communicates with the atmosphere through the automatic valve 22. The elongated portion of the piston 19 has an annular groove 20, through which the compression chamber 23 can communicate with the reservoir 25 when the piston 19 is in the upper deadpoint. The receiver 25 is put in communication with the cylinder space through the pipe 26 and the admission orifice 17, when the auxiliary piston 11 approaches its upper deadpoint. The cylinder head carries an automatic valve 21 serving for admitting separately the fuel.

The four stroke cycle engine illustrated in Fig. 2 works in the following manner: When the main piston 19 descends after the explosion, air is drawn into the chamber 23 through the valve 22 from the atmosphere by the compressor piston. When the orifice 18 is opened by the main piston 19, the exhaust begins. At this time the auxiliary piston 11 closes the admission orifice 17 and cuts off its connection with the reservoir 25. During the next stroke, there is compression on the one hand of the gas residue remaining in the cylinder after closing the orifice 18 and on the other hand of the quantity of air drawn in into the chamber 23. Toward the end of this stroke the chamber 23 communicates with the reservoir 25 through the groove 20, so that the quantity of air, compressed in the chamber 23, can enter the reservoir 25. During the next stroke a new quantity of atmospheric air is drawn into the chamber 23 through the valve 22. Simultaneously in the cylinder space a vacuum is produced by cooling down the gas residue. This under-pressure may be increased by improving the preceding exhaust by the suction action of a ventilator or by other suitable means. Consequently the valve 21 will be opened and the fuel is drawn in through the small orifice arranged at the cylinder head during the third stroke, the fuel being mixed only with the small quantity of air absolutely necessary to its vaporization. Toward the end of the suction stroke, the pis-

ton 11, approaching its upper deadpoint, cuts off the connection between the orifice 18 and the exhaust 8 and produces a free passage between the reservoir 25 and the orifice 17. Now when the working piston 19 opens 70 the orifice 17, the quantity of compressed combustion air, contained in the reservoir 25, can enter the cylinder space where it is mixed with the vapors of the fuel. The valve 21 will be closed and the fuel admission be finished as soon as the pressure in the cylinder is equal to the atmosphere. The introduction of the combustion air coming from the reservoir 25 will cease, when the pressures in the cylinder and the reservoir 80 equalize each other. Nearly at the same time the piston 19 on ascending will close the orifice 17 and then the new charge of air and fuel is compressed. An escape of fresh gases through the orifice 18 is avoided 85 by the piston 11. Toward the end of this stroke the new quantity of air, compressed in the chamber 23, is introduced into the reservoir 25 through the groove 20. The cycle recommences after the explosion of 90 the fresh charge and during the first and the second stroke of this cycle a further quantity of air is sucked in into the chamber 23, compressed there and then forced in into the reservoir 25. In this way on every 95 cycle a quantity of air, corresponding to the double volume of the chamber 23 enters in the cylinder.

The Figs. 3 to 5 show a two cylinder four stroke cycle engine in which the gas distributing system according to my invention is employed. In this case my invention gives the advantage that the gas control of both the cylinders can be effected by means of the same auxiliary devices putting in communication the orifices of the two cylinders alternately with the inlet and exhaust pipe, the main pistons opening the appertaining cylinder orifices at the proper moment toward the end of the stroke.

In Fig. 3 the two main pistons 31 and 32 moving respectively in the cylinder 33 or 34 and acting upon the engine shaft 35 are shifted relatively to each other through 180°. Every cylinder has one or more orifices 100 situated toward the end of the stroke. For instance, as shown specially in Fig. 4, two orifices 36 or 37 may be arranged respectively in the cylinder 33 or 34. These gas orifices are put in communication alternately 105 with the inlet 38 and the exhaust 39—see Fig. 4—by means of the distributor piston 40, driven at half speed by the shaft appertaining thereto by means of a suitable gearing in a well known manner.

The diagram represented in Fig. 6 gives the relation of the circle of the distributor crank to the cylinder orifices. It is assumed in Fig. 6 the orifices 36 and 37 of the two cylinders 33, 34 are arranged at the same 110

level and have the same height "a", and the distributor 10 is shifted relatively to the main pistons 31, 32 so that its crank is 45° in advance of the exterior deadpoint when the piston 32 attains its exterior deadpoint, the engine running in the sense of the arrow shown in Fig. 6. The points "A", "B", "C", "D", shifted through 90° relatively to each other denote the four positions occupied by the distributor 40 in the different corresponding deadpoints respectively of the main piston 31 or 32. Then the cycle of operation of the two cylinder engine takes place according to the following scheme:

	Distributor 40.	Piston 31.	Piston 32.
Position A..... Communication with exhaust 39.		Upper deadpoint... Explosion, orifice 36 closed.	Lower deadpoint. Exhaust, orifice 37 open.
Position B..... Communication with exhaust 39.		Lower deadpoint... Exhaust, orifice 36 open.	Upper deadpoint. Orifice 37 closed.
Position C..... Communication with inlet 38.		Upper deadpoint... Orifice 36 closed.	Lower deadpoint. Suction, orifice 37 opened.
Position D..... Communication with inlet 38.		Lower deadpoint... Suction, orifice 36 open.	Upper deadpoint. Explosion, orifice 37 closed.

The compression of the charge takes place in the cylinder 34 during the stroke "C—D", in the cylinder 33 during the stroke "D—A" after the closing of the orifice 36 or 37 respectively by the piston 31 or 32. The vacuum necessary for drawing the fresh charge into the cylinder may be produced in the engine shown in Figs. 3 to 5 in the same manner as in the engine illustrated in Fig. 1 or 2. It will be seen that this two cylinder engine has a great simplicity of construction and of working because besides the working parts of the engine itself only a single auxiliary device driven crank and connecting rod is necessary for controlling the gases of both the cylinders. The phase-displacement between the cranks of the distributor and the main pistons may have any suitable value. In choosing the phase displacement shown in the diagram of Fig. 6 there is the particular advantage that the distributing system enables the two cylinder engine to run in both directions of rotation without employing the usual reversing devices.

Having thus described my invention I declare that what I claim as new and desire to secure by Letters Patent is:—

1. In a four stroke cycle internal combustion engine the combination with the working cylinder of inlet and outlet passages situated in the cylinder wall toward the end of the outward stroke, a reciprocating power piston controlling alone the duration respectively of the admission and the ex-

haust through said passages toward the end of the outward stroke and the commencement of the inward stroke, an inlet pipe, an exhaust pipe, distributing means serving only to complete the way for the gases entering and escaping through said passages respectively toward the inlet and outlet pipe, and mechanical transmission means driving said distributing means at half the speed of the engine. 75

2. In a four stroke cycle internal combustion engine in combination a working cylinder having orifices situated toward the end of the outward stroke and common for both the admission and exhaust of gases, a power piston controlling alone said cylinder orifices toward the end of the outward stroke and the beginning of the inward stroke, a distributing device putting said cylinder orifices in communication respectively with the inlet or exhaust pipe and mechanical transmission means for driving said distributing device from the engine shaft at half the speed and with a coincidence of the deadpoints of the distributing device and the main piston. 85

3. In a four stroke cycle internal combustion engine the combination with the working cylinder of ports situated toward the end of the outward stroke, a power piston controlling alone the duration of both the admission and the exhaust of the gases entering and escaping respectively through said ports, an inlet pipe, an outlet pipe, distributing devices, putting the cylinder space in communication with the inlet pipe and cutting off its communication with the outlet pipe during the admission period and establishing communication between the cylinder space and the exhaust pipe and cutting off its connection with the inlet pipe during the exhaust period, and mechanical means for driving said distributing device at half speed from the engine shaft. 95

4. In a four stroke cycle internal combustion engine two working cylinders, each having ports situated toward the end of the outward stroke, two power pistons shifted relatively to each other through 180° each working in one of the two cylinders and controlling alone the duration of the admission and exhaust through said adjacent cylinder ports, distributing means common to both the cylinders and serving to direct the gases entering and escaping through said ports respectively of the one and the other of the two cylinders toward the inlet or outlet pipe and mechanical transmission means for driving said distributing means at half the speed of the engine. 110

5. In a four stroke cycle internal combustion engine in combination two cylinders each having orifices situated toward the end of the outward stroke and common for both the admission and exhaust of gases, two 125

- power pistons shifted relatively to each other through 180° , one working in one of the two cylinders and opening said adjacent orifices toward the end of its outward stroke, 5 the other moving in the other cylinder and opening said adjacent orifices toward the end of its outward stroke, a single distributor device common for both the cylinders and connecting said orifices of the two cylinders alternately with the inlet and 10 exhaust pipe and mechanical transmission means for driving said distributing device at half speed from the engine shaft.
6. In a four stroke cycle internal combustion engine two cylinders each having orifices situated toward the end of the outward stroke and common for both the admission and the exhaust of gases, two power pistons shifted relatively to each other through 180° 15 one working in one of the two cylinders 20 and controlling said orifices appertaining thereto, the other moving in the other cylinder and controlling said orifices appertaining thereto, a single distributing device common for both the cylinders and connecting 25 said orifices alternately with the inlet and the exhaust pipe and mechanical transmission means for driving said distributing device from the engine shaft at half speed and with an angle of lag of 45° relatively 30 to one of the two main pistons.
- In testimony whereof I affix my signature in presence of two witnesses.

HENRI PIEPER.
